UNITED STATES PATENT OFFICE

141,000

DESIGN FOR A TOY ANIMAL FIGURE

Louise Ross Laskey, Kew Gardens, N. Y., assignor to Manning Industries, Inc., New York, N. Y., a corporation of New York

Application December 23, 1944, Serial No. 117,070

Term of patent 14 years

(Cl. D34—15)

To all whom it may concern:

Be it known that I, Louise Ross Laskey, a citizen of the United States, residing at Kew Gardens, Long Island, in the county of Queens and State of New York, have invented a new, original, and ornamental Design for a Toy Animal Figure, of which the following is a specification, reference being had to the accompanying drawings, forming part thereof.

In the drawings:
Fig. 1 is a side elevational view of a toy animal figure showing my new design;

Fig. 2 is a front elevational view thereof.

I claim:

The ornamental design for a toy animal figure, substantially as shown.

LOUISE ROSS LASKEY.
